UNITED STATES PATENT OFFICE.

HANS F. RICHTER, OF WINSTON-SALEM, NORTH CAROLINA, ASSIGNOR TO R. J. REYNOLDS TOBACCO COMPANY, OF WINSTON-SALEM, NORTH CAROLINA, A CORPORATION OF NEW JERSEY.

MACHINE FOR ASSEMBLING METAL RECEPTACLES.

1,136,555.

Specification of Letters Patent. Patented Apr. 20, 1915.

Application filed December 6, 1913. Serial No. 804,991.

To all whom it may concern:

Be it known that I, HANS F. RICHTER, a citizen of the United States, residing at Winston-Salem, in the county of Forsyth 5 and State of North Carolina, have invented new and useful Improvements in Machines for Assembling Metal Receptacles, of which the following is a specification.

This invention relates to a machine for 10 assembling metal receptacles such as cans, boxes and the like and the covers therefor, particularly covers that are hinged to the cans or boxes, and has for its object to provide improvements in machines of a type in 15 the operation of which receptacles and their covers each with a hinge member thereon, are fed along separate channels and afterward brought together to be delivered later to mechanism forming a part of the machine 20 that engages the hinge member on the receptacle with the hinge member on the cover, and to a die punch that clenches the hinge members of the receptacle and cover securely together. The receptacle with its cover 25 hinged thereon then passes from the die punch, the cover, being closed over the receptacle as it progresses by suitable devices, upon a table, rack, or other support and there collected in an orderly row ready for removal. This machine may be operated alone 30 or in connection with a machine for forming beads on the open ends of the receptacle, a single driving shaft being common to both machines. Under such conditions, the receptacles are delivered from the beading 35 machine directly into the feeding channel of the clenching machine, the covers are fed by hand or otherwise into the cover channel.

In the accompanying drawings showing 40 one embodiment of the invention:—Figure 1 is a front elevation of the complete machine. Fig. 2 is an elevation from the receiving or feeding end. Fig. 3 is a plan view looking in the direction of the arrow 45 3, Fig. 2. Fig. 4 is a fragmentary detail view showing the receptacle feeding device. Fig. 5 is a view of the cover feed and cover hopper into which the covers are delivered, viewed in the direction of the arrow 5, Fig. 50 2. Fig. 6 is a transverse sectional view on the line 6—6, of Fig. 3. Fig. 7 is a similar view on the line 7—7. Fig. 8 is a sectional view on the line 8—8. Fig. 9 is a view similar to Fig. 8, with the parts in a slightly

different position. Fig. 10 is an enlarged 55 sectional view of the upper part of a receptacle, its cover and a fragment of the machine in position to have the hinge clenched. Fig. 11 is a view similar to Fig. 10, including the clenching punch in the 60 act of completing the fastening of the hinge. Fig. 12 is a cross sectional view on the line 12—12 of Fig. 3, showing how the cover after the hinge connection is finished, is partly closed over the receptacle. Fig. 13 65 is a like sectional view on the line 13—13 showing the means for fully closing the cover over the receptacle. Fig. 14 is a perspective view of one form of cover as it is fed into the machine. Fig. 15 is a similar 70 view of the upper end of a receptacle adapted to receive the cover shown.

In the drawings, 20 indicates a bed plate upon which is supported the frame work and operative parts of the machine. Bolted 75 on top of the bed plate at or near the center thereof are two upright standards 21 parallel to each other and spaced apart for a vertically movable ram or plunger 22 fitted in guides on said standards and reciprocated by a crank 23 on a shaft 24 turning in bearings also on the standards. A pitman 25 extends from the crank 23 to the ram 22 for reciprocating the same. A die punch 26 with a suitably shaped lower 80 end is fastened on the bottom of the ram to clench the hinge connections between the receptacles in the form of cans and their covers.

From the left of the machine, as seen in 90 Figs. 1 and 3, extends a horizontal trough or guide 27 along which cans or boxes A, (this being the form of receptacle illustrated in the drawings), travel to the clenching die. This trough or guide is made in 95 the present instance of two angle plates 28, 29, rigidly fastened by suitable connections, to maintain them correctly spaced, and transversely inclined, the rear angle plate 28 being higher than the front angle plate 100 29 as shown, to maintain the cans at a proper angle to engage the covers. At the bottom of the trough or guide 27 in the center thereof is a longitudinally reciprocating bar 30 on which are pivoted a number of fingers 31 spaced apart, that are held by springs 31^a perpendicular to the cans when the bar is moved toward the machine 105.

so as to engage each behind a can and advance said cans, but when said bar is moved in the opposite direction, the fingers yield and pass below the cans to the rear thereof, 5 then rise again behind them and move them forward with the next forward movement of the bar.

Supported upon the bed plate 20 in front of the ram and forming a continuation of 10 the trough or guide 27 is a channel plate 32 inclined upwardly at its rear similar to the trough and grooved in its longitudinal center for a reciprocating slide bar 33 from one end of which a lug 34 depends for moving said bar. A link 35 is connected to the lug 34 and to the free end of an arm 36 on a rock shaft 37 from which shaft projects a second arm 38 vibrated by a connecting rod 39 pivoted at one end thereto, and 15 at its other end to a crank pin 40 on the driving shaft 24. Extending transversely across the slide bar 33 are a number of cross pieces 41, shorter than said cams and spaced apart a distance slightly greater than 20 their width, on the ends of which cross pieces are pivoted fingers 42, that operate in a similar way to the fingers 31, and are maintained perpendicular to the cans each by a spring 43 holding a finger against a 25 stop pin 44. The pair of fingers 42 on each cross piece 41 receive the cans A from the trough or guide 27 and carry them by an intermittent movement through the machine past the cover hopper 45 where during a 30 pause the covers B are placed in position over the mouths of the cans, then to the punch 26 where again pausing the hinges connecting the covers and cans are clenched, then past a closing means, to be described 35 later, for closing the covers over the cans and finally to a chute 46 where the covered cans are ejected from the machine.

Above the trough 27 and the channel plate 32 are a series of friction bars 47 45 that press upon the cans and hold them in engagement with the fingers 31, 42 permitting said cans, however, to slide to a limited extent transversely of their direction of movement through the machine to receive their covers and interengage the hinge 50 members. The under faces of the friction bars 47 are preferably covered with felt 48 or some other material that will maintain the cans in any position to which they may 55 be moved. The friction plates are carried on arms 49 hinged on the front side of the trough or guide 27 and the slide plate or channel 32, pressure on the cans being regulated by screws 50 threaded in arms 51, 52 60 that are pivoted to swing over the friction plates so that the screws 50 may press thereon. Upon loosening the screws 50, the arms 51, 52 may be turned laterally and the friction plates 47 swing outwardly to permit access to the can slide and fingers in the 65

trough 27 and channel 32 should such be necessary.

Behind the rear plate 28 of the trough or guide 27 and parallel therewith is a strip or bar 53 that with said plate 28 forms a 70 horizontal duct 54 along which the covers B are brought to the hopper 45. The bottom of this duct is formed by an endless belt 55 passing around a driving roller 56 near said hopper and a guide roller 57 at 75 the outer end of the guide trough 27. A second shorter belt 58 supported on rollers 59, 60 runs above the belt 55 at its inner end and spaced therefrom sufficiently far to grasp the front and rear sides of the covers 80 B and deliver them directly into the hopper 45, see Fig. 5. On the shafts of the belt rollers 56, 59, are driving pulleys 61, 62, respectively, around which a belt 63 passes that runs over a pulley 64 on the 85 main shaft 24 and is guided by idle pulleys 65 on one of the standards 21.

The machine herein illustrated is designed to secure upon cans A that have hinge members, preferably pintles *a* properly fastened thereon, as in Fig. 15, covers B formed with open hinge members in the form of hooks *b*, see Fig. 14, that stand substantially vertical with a slight rearward inclination when the covers are in the hopper, 95 Fig. 7.

The hopper 45 is supported on the rear side of the channel plate 32 a short distance within its receiving end, and is inclined backwardly a short distance from a 100 vertical position, as clearly shown in Fig. 7, to present the covers B properly to the cans A that are inclined from the horizontal, the axial planes of the cans and covers forming an obtuse angle. The width of the hopper is slightly in excess of the height of the cover that it may move freely therein and, in the present instance, large enough to contain two covers supported sidewise, one upon the other, as in Fig. 5. The rear side of the lower cover rests on the bottom of the hopper 45, one of its ends being held against a wall 66 by a spring actuated finger 67 that yields to permit the cover to pass out of the hopper. Over the hopper is a horizontal 105 lever 101, one end fulcrumed at 102 and having a pin 103 projecting rearwardly from its other end. Between its ends is pivoted a finger 104 that extends downwardly into the hopper 45. At each descent of the ram 22 110 the pin 103 is struck thereby, which swings the lever 101 downwardly and causes the finger 104 to press upon the covers B in the hopper and force them downward should they get caught or otherwise fail to drop by gravity to the bottom of the hopper. On the return of the ram, a spring 105 115 raises the lever 101 and the finger 104. At the completion of each forward reciprocation of the slide bar 33, the mouth of a can 120

A will be brought in exact alinement with the lower cover B in the hopper 45, its bottom resting over a push plate 68 fixed on the end of a slide 69 movable in a seat in 5 the channel plate 32 and held retracted by a spring 70. The push plate is advanced to push the mouth of the can within the cover by an arm 71, pivoted to the slide 69, fixed on one end of a shaft 72 extending through 10 the channel plate and provided with a lever 73 on its other end, the free end of said lever, which may have a friction roller thereon, being moved by a cam lug 74 on the under side of the slide bar 33 during the 15 retraction of said bar. The mouth of the can is first pushed into the cover by the push plate 69 sufficiently far to carry the pintle *a* beyond the ends of the hooks *b* which latter support the mouth of the can, 20 as in Fig. 8, its base, the only other point of support resting on the channel plate 32, the can being held on these two points of support by the friction bar 47. Upon the next forward movement of the slide bar 33, the 25 fingers 42 thereon carry both can and cover beneath the ram 22, the die punch 26 thereon being immediately over the hinge members. During this movement, the bottom of the can passes off the push plate 68 and onto a 30 spring actuated plate 75 that is substantially in line with the push plate 68 when in its advanced position and is held by said plate within the cover. The hinge hooks *b* are here supported on their under sides 35 by a die block or anvil 76, Fig. 11, in the upper surface of which is a shallow groove 77 to assist the punch 26 in the formation of the hinge. During the descent of the ram and before the die punch 26 encounters the 40 hooks *b*, the can is pushed downward and out of the cover sufficiently far to permit the hinge members thereon to interengage by the following mechanism: A plate 78, Fig. 2, bolted on the ram and having a cam 45 groove 79 therein actuates through said cam groove a lever 80, Fig. 8, pivoted on the channel plate 32 and having a slot 81 therein, through which passes the cross bar of a yoke shaped frame 82, the legs 83 of which slide 50 in bearings in a bracket 84, Fig. 9, grooved on one side at 85 to form a holder to receive the cover B. The ends of the legs 83 engage the upper edge or mouth of the can A and push the same downwardly against 55 the spring pressed plate 75 until the openings *a'* between the pintle *a* and the rear side of the can are above and in line with the ends of the hooks *b* on the cover, whereupon the can, because of the downward pressure of the friction bar 47 drops upon the die block, the ends of the hooks *b* entering the openings *a'* see Fig. 10. The die punch 26 grooved at 86 on its under side then presses upon the hooks *b*, that, owing to the 60 shape of the groove, are bent over the pintle 65 *a*, as in Fig. 11, to complete the hinge connection. The next forward movement of the slide bar 33 carries the can and its cover from beneath the ram and brings another thereunder. The bottom of the can leaving 70 the ram passes from the pressure plate 75 against one side 87 of the channel plate 32, while the top of the can and cover are supported on a bar 88, a continuation of the die block 76. Upon this bar is a cam surface 75 89, that pressing upon the cover, partly closes the same over the can, as in Fig. 12. From here, on the next movement of the can, the cover B is brought in contact with a roller 90 that completely closes the cover 80 over the can. This roller is yieldingly supported on one end of a lever 91 fulcrumed at 92 to the channel plate 32, and has a spring 93 connected to its other end sufficiently strong to hold the roller 90 against the can 35 cover and close it, but which will yield and permit the can to pass, if for some unexpected cause the cover is prevented from closing, and thereby avoid injury either to can or its cover. After passing the roller 90 95, the can escapes the friction bars 47 and comes in contact with an upwardly inclined plate 94 that raises the forward side of the can sufficiently to give it a quarter turn whence it falls upon the inclined chute 46 95 down which it runs in front of a push plate 95 onto an inclined gathering rack or table 96 where the completed cans are lined up for packing. The push plate 95 is advanced to forward the cans on the rack 96 at each 100 operation of the machine by an arm 98 on the rock shaft 37 pivoted to a slide bar 97 below the channel plate 32, from which slide bar an arm 99 projects forward and is fastened to a stem 100, on the push plate. 105

In operation, the main shaft 24 rotates continuously to raise and lower the ram, drive the cover feeding belts 55, 58, and, through the connecting rod 39 and connections, reciprocate the receptacle feed bar 33. 110 Covers B are placed with their rear sides, upon which are the hinge members *b*, on the belt 55 and carried by said belt and its companion belt 58 into the hopper 45. Receptacles, in the present instance flat cans 115 or boxes with two opposite sides rounded and open at one end with a pintle *a* on one flat side of the open end, are placed with the side containing the pintle downward, in the trough or guide 27 and intermittently 120 fed by the fingers 31, 42 on the respective feed bars 30, 33 past the hopper 45, the ram 22 and the cover closing devices into the chute 46. The cans or boxes are held in engagement with the feeding fingers and in 125 any position into which they may be moved by the friction bars 47. At the end of each forward movement of the feed bar 33, the cans stop while the feed bar returns to reengage the cans. At each pause in the travel 130

of the cans one of them stops opposite the hopper 45 in line with the lower cover B therein. With each return of the feed bar, the cam block 74 thereon actuates the arm 71 and slide plate 68, against which the bottom of the can is resting, and pushes said can in a direction transverse to the line of feed to cause its mouth to enter the cover B in the hopper. This movement of the can 10 carries the hinge member or pintle *a* thereon beyond the hinge member *b* on the cover so that the rear side of the can is supported just below the pintle, upon the ends of the hooklike hinge member *b*. The next forward movement of the feed bar 33 carries the can and its cover, which is partly on the can, beneath the ram where there is another pause while the feed bar returns. During this pause of the can, the ram with its die 20 punch 26 and cam plate 78 descend, the cam plate first swinging the lever 80 to slide the yoke frame 82, the legs 83 of which engage the mouth of the can and push it a short distance out of its cover against the 25 spring actuated plate 75, the movement being only sufficient to register the spaces *a'* between the pintle *a* and the side of the box, with the hook ends of the hinge member *b* on the cover. Immediately the hinge members *a* and *b* are interengaged by the downward pressure of the friction bar 47 above the can, the ends of the hinge member projecting nearly vertical with a slight rearward inclination toward the cover, see Fig. 30 10. The can at this time is supported at its bottom on the channel plate 32 and at its top on the die block 76 with the hinge members in the shallow groove 77 of said block, its longitudinal axis lying at an angle 40 to the horizontal with the mouth end higher than the bottom. The cover is also in an inclined position and supported in the groove 85 in bracket 84, the axis of the cover corresponding to the longitudinal axis of the 45 can being inclined in the opposite direction and forming an obtuse angle therewith greater than one hundred and eighty degrees. The opening thus left between the can and the cover affords sufficient room for 50 the die punch 26 to enter and clench the hinge members. The groove 86 in the bottom of the die punch encounters the ends of the hinge member *b* near the end of the downward stroke of the ram and by its 55 shape, curls said member over the pintle *a* in the manner indicated in Fig. 11. The ram now rises and the can and cover are carried from below the same by the feed bar 33, the cover B during the movement 60 coming in contact with the fixed cam surface 89 that partly closes the cover over the can. After a pause the can advances again past the yieldingly supported roller 90 that completely closes the cover over the can. 65 The next movement of the can carries it

from beneath the friction bar 47 and against an inclined plate 94, its side upon striking this inclined plate is raised and the can caused to make a quarter turn before sliding down the chute 46 on one of its narrow sides to an inclined tray or table in front of the push plate 95 that moves the newly completed can against the previously deposited ones and advances all on the tray a short distance. 70

What I claim is:—

1. In a machine of the character described, means for feeding forward parts of a receptacle including a formed body and a formed cover therefor, said parts having hinge members, means for guiding said parts so as to bring the hinge member of one part into position projecting adjacent to the hinge member of the other part, and means for clenching the hinge members 80 thereafter to effect an interlocking engagement therebetween. 85

2. In a machine of the character described, means for feeding forward parts of a receptacle including a formed body and a formed cover therefor, said parts having hinge members, means for guiding said parts so as to bring the hinge member of one part into position projecting across and adjacent to the hinge member of the other 90 part, and means for clenching the hinge members thereafter to effect an interlocking engagement 95 therebetween.

3. In a machine of the character described, means for feeding forward parts to a receptacle including a formed body and a formed cover therefor, said body and said cover having the one a pintle and the other a hinge member with a projecting tongue, means for moving one of said parts laterally 100 toward the other so as to bring said tongue into position adjacent and projecting across said pintle, and means for clenching the tongue around the pintle thereafter. 105

4. In a machine of the character described, in combination, means for feeding forward formed receptacle covers having hinge members, means for feeding forward formed receptacle bodies having hinge members, means for guiding said bodies so as to bring the mouth of each body into a position in which it projects into its corresponding cover, means for then relatively moving the receptacle body and its corresponding cover to inter-engage said hinge members, and 110 means for effecting the interlocking of said hinge members thereafter. 115

5. In a machine of the character described, in combination, means for feeding forward formed receptacle covers having hinge members, means for feeding forward formed receptacle bodies having hinge members, means for guiding said bodies so as to bring the mouth of each body into a position in which it projects into its corresponding 120 125 cover, 130

- cover, means for then relatively moving the receptacle body and its corresponding cover to inter-engage said hinge members with the cover in an open position, and a member 5 guided to move into the space between the cover and the body to clench said hinge members thereafter.
6. In a machine of the character described, in combination, an anvil, means for feeding 10 forward a formed receptacle cover having a projecting hinge member into a position with said projecting hinge member adjacent to said anvil, means for feeding forward a formed receptacle body having a hinge member, means for guiding said body so as to bring the hinge member thereof into 15 position adjacent said anvil and adjacent the projecting hinge member of said cover, means for then moving said cover and body 20 relatively to each other to inter-engage said hinge members with the cover in an open position, and means coöperating with said anvil to interlock said hinge members together.
- 25 7. In a machine of the character described, in combination, an anvil, means for feeding forward a formed receptacle cover having projecting hinge members into a position with said projecting hinge members 30 adjacent to said anvil, means for feeding forward a formed receptacle body having a hinge member, means for guiding said body so as to bring the hinge member thereof into position adjacent said anvil and ad- 35 jacent the projecting hinge member of said cover, means for then moving said cover and body relatively to each other to inter- 40 engage said hinge members with the cover in an open position, and a member guided through the opening between the cover and the body and coöperating with said anvil to clench said hinge members together.
- 45 8. In a machine of the character described, in combination, means for feeding forward formed receptacle covers having hinge members, means for feeding forward a plurality of formed receptacle bodies having hinge members, by a step by step move- 50 ment, means for guiding said bodies so as to bring the mouths of each of said bodies successively into a position in which it projects into its corresponding cover, said guiding means including a guide bar extending in the direction in which said bodies are 55 fed forward, and having means for yield- 60 ingly engaging said bodies to hold the same, means for relatively moving each body and its corresponding cover to inter-engage the hinge members thereof, and means for clenching the hinge members together there- 65 after.
9. In a machine of the character described, in combination, means for feeding forward formed receptacle covers having hinge members, means for feeding 70 forward a plurality of formed receptacle bodies having hinge members, an anvil, means for holding the cover at said anvil with its hinge member adjacent to said an- 75 vil, means for guiding the receptacle body into an inclined position with respect to the held cover with its hinge member adjacent to the hinge member of the held cover, means for relatively moving the receptacle body and its corresponding cover to inter- 80 engage the hinge members thereof with the cover in an open position with respect to the body, and a member guided into the opening between the cover and the body and co- 85 operating with said anvil to clench said hinge members together.
10. In a machine of the character de- 90 scribed, in combination, a guide-way adapted to receive a plurality of receptacle bodies having hinge members, a guide bar opposite said guide-way and having a pad yield- 95 ingly engaging the receptacle bodies, an anvil, a holder for the cover adjacent to said anvil, means for feeding receptacle cov- 100 ers having hinge members successively into said holder with the hinge members of the cover disposed adjacent said anvil, feeding means associated with said guide-way for advancing the receptacle body into position opposite said holder, means for relatively moving the cover and the receptacle body to inter-engage the hinge members thereof, and means coöperating with said anvil to clench the hinge members together.
11. In a machine of the character de- 105 scribed, in combination, a guide-way adapted to receive a plurality of receptacle bodies having hinge members, a guide bar opposite said guide-way and having a pad yieldingly 110 engaging the receptacle bodies, an anvil, a holder for the cover adjacent to said anvil, means for feeding receptacle covers having hinge members successively into said holder with the hinge members of the cover dis- 115 posed adjacent said anvil, feeding means associated with said guide-way for advanc- 120 ing the receptacle body into position oppo- site said holder, with the hinge member thereof over the hinge member of the cover, means for engaging the body to shift the same longitudinally to inter-engage said hinge members, means for yieldingly engag- 125 ing the bottom of the body and means co- operating with said anvil to clench said hinge members.
12. In a machine of the character de- 130 scribed, means for separately feeding there- into metal receptacles and covers therefor each with a hinge member thereon, means for placing a cover partly on a receptacle and interengaging said hinge members, means for connecting together said hinge members, and means for closing the cover over said receptacle after fastening said hinge members.

13. In a machine of the character described, means for separately feeding thereinto metal receptacles and covers therefor each with a hinge member thereon, means for placing a cover partly on a receptacle and interengaging said hinge members, means for connecting together said hinge members, means for closing the cover over said receptacle after fastening said hinge member, and means for turning the completed receptacles and assembling them in line.

14. In a machine of the character described, a reciprocating means for feeding thereinto receptacles having a hinge member, means for feeding thereinto covers each with a hinge member, a hopper into which said covers are delivered, means for moving each of said receptacles transversely to the direction of feed into a cover, means for interengaging the hinge members of said parts, a fixed die, and a coöperating movable die for connecting together said hinge members.

15. In a machine of the character described, a reciprocating feed bar, spaced pairs of fingers pivoted on said bar adapted to engage and move in one direction only receptacles each having a hinge member, a continuously moving means for feeding covers each with a hinge member into said machine, a hopper into which said covers are delivered, means for moving each of said receptacles transversely of said feed bar into a cover, means for interengaging the hinge members of said parts, and means for connecting together said hinge members.

16. In a machine of the character described, a reciprocating feed bar, spaced pairs of fingers pivoted to said feed bar adapted to engage and move in one direction only receptacles each having a hinge member, a continuously moving means for feeding covers into said machine, a hopper into which said covers are delivered, means for moving each of said receptacles transversely of said feed bar into a cover; friction bars bearing on said receptacle to hold them in engagement with said fingers and in any position into which they may be moved, means for interengaging the hinge members of said parts, and means for connecting together said hinge members.

17. In a machine of the character described, a reciprocating feed bar, spaced pairs of fingers pivoted on said bar, adapted to engage and move in one direction only receptacles each having a hinge member, a continuously moving means for feeding covers each with a hinge member thereon into said machine, a hopper into which said covers are delivered, means for moving each of said receptacles transversely of the feed bar into a cover, friction bars bearing on said receptacles to hold them in engagement

with said fingers and in any position into which they may be moved, means for moving said receptacle in a reverse direction across the feed bar to cause the interengagement of said hinge members, means for connecting together said hinge members, and means for closing the covers over the receptacles.

18. In a machine of the character described, a reciprocating feed bar, spaced pairs of fingers pivoted on said bar adapted to engage and move in one direction only metal receptacles each having a hinge member, friction bars above said feed bar adapted to press upon said receptacles and hold them in engagement with said fingers and in any position into which they may be moved, hinged connections for said friction bars to permit swinging the same from above the feed bar, and pressure regulating means for said friction bars.

19. In a machine of the character described, a channel through which receptacles having a hinge member are fed into said machine, a reciprocating feed bar in the bottom of said channel, spaced pairs of fingers pivoted on said bar adapted to engage and move said receptacles in one direction only in said channel, friction bars above said channel for retaining the receptacles therein, hinge connections between said bars and said channel, pressure regulating means for said friction bars, a continuously moving means for feeding covers each with a hinge member thereon into the machine, means for fitting covers to the receptacles, means for interengaging the hinge members of the receptacles and covers, and means for clenching said hinge members.

20. In a machine of the character described, means for feeding separately thereinto receptacles and covers therefor each with a hinge member thereon, a transversely reciprocating push plate for moving said receptacles each into a cover, a spring actuated plate and a coöperating positioning means for adjusting each receptacle to engage the hinge member thereof with the hinge member of the cover, and means for clenching the hinge member.

21. In a machine of the character described, means for feeding separately thereinto formed receptacle bodies and formed covers therefor each with a hinge member thereon, means for engaging the cover with the body, a reciprocating ram, means actuated by said ram for causing the interengagement of the hinge members of the body and its cover, and a die punch carried by said ram for clenching said hinge members.

22. In a machine of the character described, means for feeding separately into said machine formed receptacle bodies and formed covers therefor, each with a hinge member thereon, means for placing a cover

partly on a body, a reciprocating ram and a die punch carried by said ram, means actuated by said ram for interengaging the hinge members of the body and its cover, 5 and a fixed die coöperating with said die punch for clenching said hinge member.

23. In a machine of the character described, means for feeding thereinto formed receptacle bodies and formed covers there-
10 for each with a hinge thereon, means for bringing a body and a cover together and interengaging the hinge members thereof, a reciprocating ram provided with a die punch, and a fixed coöperating die for
15 clenching said hinge members.

24. In a machine of the character de-
scribed, means for intermittently feeding

formed receptacle bodies having hinge mem-
bers into and through said machine, means for
feeding formed covers with hinge memebrs 20
for said bodies into said machine, and a plu-
rality of coöperating mechanisms adapted to
successively place a cover on a body, inter-
engage the hinge members of the body and
cover, and clench said hinge members dur- 25
ing the pauses in the operation of the feed-
ing mechanism.

In testimony whereof I have hereunto set
my hand in presence of two subscribing wit-
nesses.

HANS F. RICHTER.
